HOLDER FOR POSITIONING AND SHARPENING HYPODERMIC NEEDLES

Edward F. Rugels, Long Beach, Calif., assignor of one-third to Leroy E. Ridgeway and one-third to William A. Crowe, both of Long Beach, Calif.

Application April 14, 1953, Serial No. 348,695

3 Claims. (Cl. 51—221)

This invention has to do with a holder for positioning and sharpening hypodermic needles and it is a general object of the invention to provide a mechanism operable to securely and advantageously hold a hypodermic needle for operation or manipulation relative to an abrasive stone, or the like, in order to effect sharpening of the needle.

Hypodermic needles as supplied for use are sharpened, that is, they are provided with a tip end cut at an angle or beveled and dressed so that they are sharp and free of burrs. Such needles are suitable for a limited amount of service, however, they become dull with use and thus require replacement or sharpening. The usual hypodermic needle can be effectively or advantageously sharpened by means of a fine abrasive member or stone, however, persons entrusted to sharpen a needle are not always so trained or skilled as to be able to gain the desired results.

It is a general object of this invention to provide a device or mechanism in the nature of a hypodermic needle holder and which is such as to be readily operable to receive and hold a hypodermic needle with the tip end thereof so positioned as to be readily and properly sharpened when the holder is manipulated in a simple manner relative to a sharpening stone, or the like.

Another object of the invention is to provide a device of the character mentioned, that is readily serviceable to hold a needle for sharpening of the flat beveled end face thereof, and also for dressing of side edges occurring adjacent that face at the forward portion of the needle.

A further object of this invention is to provide a device of the general character referred to including a clamping means operable to effectively and dependably hold a needle in the structure against movement or shifting in the course of the sharpening operation.

It is a further object of this invention to provide a structure of the general character referred to including means serviceable to establish a given positioning of the needle relative to the body of the structure to result in a predetermined dressing or cutting away of the needle as it is worked relative to an abrasive stone or the like.

It is another object of this invention to provide a structure of the general character referred to which is of a simple inexpensive form and construction, which is of limited size, compact, and such that it can be readily handled properly.

The various objects and features of my invention will be fully understood from the following detailed description of a typical preferred form and application of my invention, throughout which description reference is made to the accompanying drawings, in which:

Fig. 1 is a view illustrating the structure of the present invention carrying a typical hypodermic needle and shown held by a user and in operating position relative to a sharpening stone.

Fig. 2 is a detailed transverse sectional view as shown in Fig. 1.

Fig. 3 is a view similar to Fig. 2 illustrating the set-

2

ting means engaged to establish a desired seat of the needle relative to the body of the device.

Fig. 4 is an end elevation of the structure shown in Fig. 3 being a view as indicated by line 4—4 in Fig. 3.

Fig. 5 is an enlarged side elevation of a needle as sharpened by means of the structure provided by the invention showing the sharpened end portion in longitudinal section.

Fig. 6 is an enlarged view of the needle shown in Fig. 5 taken as indicated by line 6—6 on Fig. 5 and showing the side edges of the sharpened end portion dressed away.

The structure as provided by the present invention is adapted to handle or hold a hypodermic needle A for the proper positioning and handling or manipulating of such needle relative to the sharpening device such as an abrasive stone B, or the like. In the drawings the stone B is shown as having a flat top face 10 to serve in cutting or sharpening the needle, and the needle A is shown as a simple, conventional, straight, tubular needle with a beveled dressed end face 12 establishing the needle with a sharp point 13. A suitable mounting or fitting 14 is shown on the needle A at the end remote from the point.

The holder as provided by the present invention is characterized by a body C having a flat bottom 15 and a needle opening 16. The structure further includes a clamp means D related to body C and serviceable to hold or clamp a needle in the body and, if desired, the structure may include a setting means E serviceable to establish a predetermined positioning of the needle relative to the face 15 of body C.

The body C as provided by the present invention is preferably a rigid unit or block of solid material and the bottom face 15 of the body, which is the critical face thereof, is preferably finished so that it is flat and smooth.

The particular body C illustrated in the drawings is in the form of a block somewhat elongate so that it has vertical side walls 20, vertical end walls 21, and a flat top 22 parallel with the bottom 15.

The needle opening 16 provided in accordance with the present invention is formed in the body C so that it is pitched or inclined relative to the bottom face of the body at which it opens. In the preferred form of the invention the needle opening 16 is formed in body C so that it enters one vertical wall of the body and extends down and in therefrom until it opens at the bottom 15. In the particular case illustrated the needle opening 16 enters the body C at one end wall 21 thereof and extends down and inward in the body to open at the bottom 15 at a point spaced somewhat inward from the other or opposite end wall 21.

The needle opening 16 may in practice be a simple, straight opening of uniform size and shape from one end to the other, however, it is preferred that instead of being of uniform size throughout its length it is formed so that it has a portion X adapted to more or less accurately fit or slidably receive the needle A while a portion Y occurring where the opening enters the end wall 21 of the body is enlarged and is in the nature of a mouth considerably larger than the needle.

In the preferred construction illustrated in the drawings the mouth portion Y of the needle opening is of substantial size and will accommodate a fitting 14 such as may occur on the needle A, and between the portions X and Y there is a neck portion Z smaller than the mouth portion Y and larger than the needle portion X and serving to effectively guide the needle into the portion X upon its being inserted into the body by way of the mouth Y.

When the needle opening 16 is formed as just described, it is preferred that the bottoms or innermost ends of the mouth and neck be beveled or inclined as shown in

the drawings to facilitate guiding of the needle into the portion X which is but slightly larger than the needle.

In accordance with the present invention the pitch or inclination of the needle opening 16 and particularly the portion X thereof relative to the plan of the bottom 15 of the body is a critical factor and in practice is preferably established so that the acute angle between the needle opening and bottom 15 is somewhere between 15 and 20 degrees.

In carrying out the invention the body C may be provided with more than one needle opening 16 as clearly shown throughout the drawings, and when this is the case the needle openings may be at different angles or pitch relative to the bottom 15 of the body. Further, in carrying out the invention it is preferred that the needle portion X of the needle opening 16 be such as to receive the needle A with limited clearance, for instance, it may be such as to slidably receive the needle and when this practice is followed different needle openings in the body C may be established having different sizes to accommodate needles of different sizes.

The means D provided by the present invention for clamping a needle in the needle opening 16 is preferably a screw means and in the form illustrated includes a screw 30 having an operating head 31 at the exterior of body C and a clamp head 32 in the body and engageable with the needle. In the construction illustrated a cavity 35 is provided in the body C intersecting the needle carrying portion X and a threaded opening 36 enters the body C from the exterior thereof and communicates with the cavity. In the case illustrated threaded opening 36 enters the body C from the top 22 thereof, the screw 30 is threaded in the opening 36 and the clamp head 32 on the screw projects into the cavity 35. In the case illustrated the operating head 31 of the screw is at the exterior of body C and projects a substantial distance up from the top 22 of the body. With the construction just described, after the needle has been inserted in the opening portion X and established in the desired position therein the screw 30 can be set or tightened causing the head 32 to engage and clamp against the needle so that it will not shift or change position relative to the body C.

The setting means E is a feature of the construction that may be employed if desired and if the structure is equipped with the means E this element is located at the end 21 of body C closest to the point at which the needle opening issues at the bottom 15 of the body. In accordance with the invention the means E includes a stop element 40 shiftable relative to the body C, and in the case illustrated this element is pivotally carried by a pivot member 41 supported by the body C. The stop element 40 has a projecting stop shoulder 43 movable into and out of position where it projects from or below the bottom 15 of body C. In Figs. 1 and 2 of the drawings the stop element is shown positioned with the stop shoulder 43 out of operating position and this position of the element 40 is indicated in dotted lines in Fig. 4. In Figs. 3 and 4 the stop element is shown in full lines in working position where the stop shoulder 43 projects below the bottom 15 of body C. In the drawings the structure just described is shown somewhat exaggerated in order to illustrate its action, that is, the stop shoulder 43 when in operating position appears to project a substantial distance below the bottom 15 of body C whereas in practice the distance that the stop shoulder 43 projects may be limited to a few thousandths of an inch.

In the preferred construction the stop element 40 is provided with a handle portion or manually engageable projection 45 and the pivot member 41 is screw threaded to the body C and holds the member 40 so that it will not shift relative to the body C unless deliberately operated.

With the construction provided by the present invention a user, desiring to sharpen a needle A, inserts the

needle into the needle opening 16 or into the preferred needle opening, assuming that the device has more than one such opening. The needle is inserted until the end face 12 thereof to be sharpened is substantially flush with the bottom 15 and body C but preferably located to project but slightly beyond or below the bottom 15, the amount of projection of the needle from face 15 can be determined by the user, as by the user feeling the needle to see that it projects as desired, or the means E can be employed as shown in Figs. 3 and 4 in which case with the body C pitched relative to a stone B or the like, the needle is inserted until it engages the stone whereupon the means D is actuated to set the needle relative to the body.

In any event when the needle is positioned where desired, whether the means E is employed or not, it is set against movement relative to the body by merely operating screw 30 so that head 32 clamps against the needle. If means E has been used it is then disengaged or moved into positions shown in Figs. 1 and 2. With the needle set relative to the body with the face 12 of the needle projecting slightly from the bottom 15 of the body, the body can be operated relative to the top 10 of stone B with resulting dressing of the tip of the needle to sharpen it. If it is desired to further trim or dress the needle, for instance, to sharpen or cut away the side edges 50 of the pointed end of the needle the operator can after finishing face 12 loosen the means D and rotate the needle in the hole 16 to bring one edge 50 slightly below face and bottom 15 whereupon means D can be actuated to clamp the needle so that it is held while that edge 50 is dressed. Following dressing of the set edge 50 the means D can be released and the needle again rotated bringing the other edge 50 in position to be dressed.

With the construction provided by the present invention a person can with very little skill or experience handle a hypodermic needle so that it is with the aid of the body C operated relative to a stone B to effect accurate and proper sharpening of the needle. With the construction provided the needle can be handled without the danger of injuring it and without danger to the operator. Furthermore, the structure as provided by the invention is of simple, compact, convenient form making it easily transported from place to place, and it is of such form as to be very easily handled or manipulated in the course of use.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. A holder for positioning a hypodermic needle having an inclined face at its sharpened end including, a rigid body having a flat bottom and a needle hole extending downwardly into the body and opening at the bottom of the body and inclined relative thereto and adapted to guide the needle through the body, means adapted to rigidly hold the needle in the hole against movement relative to the body, and releasable means adapted to position said end of the needle with its face in a predetermined position below and parallel with the bottom of the body by pitching the body relative to a supporting surface while the needle is in the hole and engaged with such support.

2. A holder for positioning a hypodermic needle having an inclined face at its sharpened end including, a rigid body with a flat bottom, vertical side walls and a top, the body having a hole entering it from one side and extending downward and inward in the body and opening at the bottom, the body having a cavity in it intersecting the hole, the hole being adapted to receive and guide the

needle through the body, means adapted to rigidly hold the needle in the hole against movement relative to the body including, a screw threaded in the body from the top thereof and having a clamp head in the cavity adapted to engage and clamp the needle, and releasable means adapted to position said end of the needle with its face in a predetermined position below and parallel with the bottom of the body by pitching the body relative to a supporting surface while the needle is in the hole and engaged with such support.

3. A holder for positioning a hypodermic needle having an inclined face at its sharpened end including, a rigid body with a flat bottom, vertical side walls and a top, the body having a hole entering it from one side and extending downward and inward in the body and opening at the bottom, the body having a cavity in it intersecting the hole, the hole being adapted to receive and guide the needle through the body, and means adapted to rigidly hold the needle in the hole against movement relative to the body including, a screw threaded in the body from the top thereof and having a clamp head in the cavity adapted to engage and clamp the needle, the screw having an oper-

10

15

20

ating head at the exterior of the body, and releasable means adapted to position said end of the needle with its face in a predetermined position below and parallel with the bottom of the body by pitching the body relative to a supporting surface while the needle is in the hole and engaged with such support.
